UNITED STATES PATENT OFFICE.

WILLIAM HENRY HOWARD, OF NEW YORK, N. Y.

DESIGN FOR A BANK-CHECK, &c.

SPECIFICATION forming part of Design No. 27,620, dated September 7, 1897.

Application filed July 13, 1897. Serial No. 644,452. Term of patent 14 years.

To all whom it may concern:

Be it known that I, WILLIAM HENRY HOWARD, a citizen of the United States, and a resident of New York, in the county of New York and State of New York, have invented and produced a new and original Design for a Bank-Check or Similar Article, of which the following is a specification.

My design will be fully understood upon reference to the accompanying drawing, which illustrates a check having the new design applied thereto.

As shown in the drawing, the leading or material feature of my design consists in a number of lines within the limits of the check proper, radiating from the center of a line extending across one end of the check, so as to form intervening triangular spaces spread out in fan shape and having their apexes at a common point. In addition to these radiating triangular spaces there may be provided a series of marginal spaces cut off from the bases

of the triangles by lines drawn parallel to the edges of the check. The triangular spaces and the series of marginal spaces provide panels upon which may be arranged any desired matter or letter-press. The main body of the check may correspond in form to checks, drafts, &c., of ordinary appearance.

While I have described my new design as being applied to checks, it is obvious that the same is applicable to other species of commercial paper, tickets, or similar articles.

Having thus described my invention, what I claim as new, and desire to secure by Letters Patent, is—

The design for a bank-check or similar article, substantially as herein shown and described.

WILLIAM HENRY HOWARD.
